UNITED STATES PATENT OFFICE.

ARTHUR F. POOLE, OF CHICAGO, ILLINOIS, ASSIGNOR, BY MESNE ASSIGNMENTS, TO THE WAHL COMPANY, OF WILMINGTON, DELAWARE, A CORPORATION.

ALGEBRAIC TOTALIZER.

1,296,118.

Specification of Letters Patent.

Patented Mar. 4, 1919.

Application filed February 27, 1913. Serial No. 751,032.

To all whom it may concern:

Be it known that I, ARTHUR F. POOLE, a citizen of the United States, residing at Chicago, in the county of Cook and State 5 of Illinois, have invented certain new and useful Improvements in Algebraic Totalizers, of which the following is a specification.

My invention is an improvement in algebraic totalizers for use in connection with calculating machines.

One of the objects of my invention is the provision of a totalizer with but a single set of carrying mechanism and from which 15 the accurate total of a series of items, whether the same be positive or negative, may be read.

Another object of my invention is the provision of a totalizer showing the correct 20 total on either one or the other of two sets of figures and having manually operated means to designate which set of figures shall be read.

Another object of my invention is the 25 provision of a totalizer having a single set of reversible carrying wheels and two sets of figures paired 0-9 associated therewith, manually operated means designating which set of figures shall be read, and means automatically inserting a unit in the totalizer 30 when the designating means is changed from one set of figures to the other.

A further object of my invention is the 35 provision of an algebraic totalizer in which the digits of a number may be inserted *seriatim* and especially adapted to operate in conjunction with calculating machines of the type described in Patent No. 893,719 issued to John C. Wahl, July 21, 1908.

40 A further object of my invention is to provide an algebraic totalizer having a visible legend which states whether the exhibited total is positive or negative and also instructs the operator whether the exhibited 45 total shall be cleared from the machine by addition or subtraction. I also provide means to change this legend according to the sign of the said total.

50 A further object of my invention is the provision of an algebraic totalizer which shall be simple in construction, positive in action and of easy manufacture.

These and other objects of my invention are described in the accompanying specification, in the drawings of which,—

55

Figure 1 is a right side elevation of my totalizer;

Fig. 2 is a front elevation with the cover removed;

Fig. 3 is a section along line 3-3 of 60 Fig. 4;

Fig. 4 is a partial top view of parts appearing below the line 4-4 of Fig. 3;

Fig. 5 is a section of the right side of a totalizer taken along the line 5-5 of Fig. 1; 65

Fig. 6 is a detail view showing the connection between the carrying gears and the two sets of number disks;

Fig. 7 is a front elevation of my totalizer 70 as it appears when exhibiting a positive total;

Fig. 8 is a front elevation of my totalizer as it appears when exhibiting a negative total.

As above stated, my invention is particularly designed to be used in connection with the calculating machine described in the aforementioned patent. Reference thereto will show a totalizer mounted on a typewriter carriage, a set of numeral keys, any 80 one of which serves to operate a master wheel 49 and a master dog 208; also that the depressing of any numeral key results in the master wheel 49 and the dog 208 moving in the following sequence: 85

(a) Dog 208 moves in a counter-clockwise direction (Fig. 1), thus unlocking the chain of the totalizer gears at the actuated gear.

(b) The master wheel rotates an amount 90 depending on the key actuated.

(c) The dog returns to its original position.

(d) The carriage escapes, bringing the totalizer wheel of the next lower order into engagement with the master wheel. A reversing handle is also provided whereby the direction of motion of the master wheel consequent upon the actuating of any key will be determined and thus numbers inserted in the machine either additively or subtractively. 100

Since the mechanism for producing these motions is very thoroughly described in the patent referred to, I shall not now enter into

a further description of such mechanism, but shall premise that the actuating of a typewriter numeral key results in the master wheel, master dog and carriage moving in the sequence recited above. The master wheel numbered 49 and the master dog 208 in my present application correspond in position and function to the master wheel and master dog bearing the same numbers in the cited patent of Wahl referred to above.

Suitably supported by its side plates 10 and 11 is a totalizer constructed similar to the totalizer of the above mentioned Wahl patent. This consists of a set of carrying gears 12 (Figs. 1 and 2) loosely mounted on a shaft 13 rigid between the plates 10 and 11 and which are adapted to coöperate *seriatim* with the master wheel 49 rotatably mounted in the framework, and a set of carryable gears 14 pivoted at 15 on a set of swinging arms 16. These arms are loosely mounted on the shaft 17 and 18, and their associated carryable gears 14 serve to connect the carrying wheels 12. Arms 16 have heels 19 adapted to be engaged *seriatim* by the master dog 208. The carrying gears 12 are provided with the usual carrying teeth which coöperate with the carryable gears 14 and thus transfer the tens at the proper time. The chain of gearing composed of the carrying gears 12 and the carryable gears 14 is normally locked. In order for the master wheel to operate on a carrying wheel at the middle of the chain the master dog 208 acts on a swinging arm 16, thereby raising the carryable gear 14 mounted thereon out of mesh with the carrying gears 12 to the right and left, thus unlocking the actuated carrying gear 12 from the next one to the right.

The totalizer is mounted on a truck 20 moving with the typewriter carriage. Numbers are inserted in the totalizer by the master wheel one digit at a time, beginning with the digit in the highest place and ending with the digit in the units place. During the insertion of a number the typewriter carriage escapes step by step to the left after the insertion of each digit, thus bringing successive carrying gears 12 into mesh with the master gear 49 and successive swinging arms 16 in a position to be acted on by the master dog 208.

The foregoing will be recognized as substantially the operation and structure of the totalizer in the above cited Wahl patent; the parts which are peculiar to my present invention are those which have to do with the indicating of positive and negative totals, and these parts will now be described.

Rigidly supported between the side plates 10 and 11 is a shaft 28 on which is loosely mounted a set of idle gears 27, there being one gear 27 meshing with each carrying gear 12 of the totalizer. Meshing with each idle gear 27 are two gears 25 and 26 rota-

tably supported on shafts 21 and 22 rigid between the side plates. Rigid with the gears 25 and 26 are the positive figure bearing disks 23 and the negative figure bearing disks 24. These have the figures from zero to nine inclusive on their periphery. There is a disk 23 and a disk 24 connected by means of an idler 26 to each carrying gear 12, and the gear connections are such that the disks 23 and 24 always revolve in the same direction. The figures on these disks are arranged to progress in opposite directions and the totalizer is so assembled that when a 9 is on the reading line for the disk 23 a 0 is on the reading line for the disk 24 and vice versa.

A suitable cover 29 for the totalizer is provided and this cover has two windows 30 and 31 through which the numbers exhibited by the disks 23 and 24 may be read. However, since but one of these numbers is desired to be read at any particular time a shutter mechanism is provided for the superfluous number. This mechanism will now be described.

Rotatably mounted on the shafts 21 and 22 are segmental gears 32 and 33. These serve as supports for the shutters 34 and 35, which extend over all the number disks on the respective shafts 21 and 22 and the shutters are riveted to the segmental gears 32 and 33. The shutters 34 and 35 are of suitable width to register with the openings 30 and 31, and when either shutter is behind its corresponding opening the numbers on the number wheels associated with that opening are, of course, concealed. The two segmental gears 32 and 33 are in mesh with an idle gear 36 rotatably mounted on the shaft 28. This idle gear in its turn is in mesh with a segmental gear 37 (best shown in Fig. 3.) rotatably mounted on the shaft 13. It will be readily seen that rotation of the segmental gear 37 will be transmitted through the idler 36 to the shutters and enable one or the other of the lines of figures to be viewed through the windows 30 or 31, according to the position of the shutters. The segmental gear 37 is held in its position by a dog 38 rotatably mounted on the shaft 18 and held in engagement with it by a spring 40.

Loosely mounted on the shaft 13 is a cam 41 which is rigidly connected to a handle 42 by studs 43 and 44, which extend through suitable slots 45 and 46 in the side plate 10. Rigid with the segmental gear 37 are two studs 47 and 48, these being of sufficient length to engage the cam 41 when the latter is rotated. It will now be seen that movement of the handle 42 will be transmitted to the cam 41 and such motion by means of the engagement of the cam 41 with the stud 47, for instance, will serve to rotate the segmental gear 37, consequently changing the shut-

ters so as to expose the alternative set of figures. Suitable studs 50 and 51 rigid in the side plate 10 serve to limit the motion of the cam 41 in either direction. It will also be noticed that the cam 41 is provided with an extension 54 which engages the dog 38 and raises the dog from its engagement with the teeth of the segmental gear 37 during the rotation of the latter.

10 It is well known that when a totalizer having a single set of reversible carrying mechanism is provided with two sets of figures from which both positive and negative totals may be read, the positive totals being read 15 from one set of figures and the negative totals from the other, and further, that when these figures are paired in the relation of 9-0, 8-1, et cetera, an extra unit must be added to the set of figures to be read every 20 time the totalizer passes through zero in either direction. For instance, assuming that a positive total is exhibited by the totalizer and that a greater number than the total exhibited is subtracted, the set of wheels 25 which had been exhibiting the positive total would now change to show a number preceded by 9's in the highest decimal places, which number would be the correct arithmetical complement of the negative total, 30 and a number would be exhibited on the set of figures from which the negative total is read, but the latter number, owing to the wheels being paired in the relation of 9-0, would be one unit less than the correct 35 amount. I have, therefore, provided mechanism operating coincidently with the shifting of the shutter which will automatically add one in the units place of the number exposed by said shifting.

40 To this end the segmental gear 37 also meshes with a pinion 52 rotatably mounted on a stud 53 in the swinging arm 16 in the units place of the totalizer. This pinion 52 is of sufficient width (Fig. 4) to engage the 45 carrying gear 12 in the units place of the totalizer; consequently every time the handle 42 is moved and the shutter shifted thereby, the pinion 52 will be rotated one step and an additional unit will be put in the units place 50 of the totalizer. The pinion 52 has rigid with it a set of star teeth 61 having notches which are adapted to engage with the locking bar 60 when said pinion is raised out of mesh with the segmental gear 37 and the 55 carrying gear in the units order. It is to be noted that as shown in Fig. 5, the segmental gear 37, instead of having a locking disk like that associated with the carrying gears 12, has this locking disk made smaller so that it 60 will not engage the teeth 61. Therefore, this disk offers no obstacle to the rotation of the gear 52 by the segmental gear 37.

It is to be noted that instead of making the disk associated with the gear 37 of 65 smaller diameter than the locking disks as

associated with the carrying gears 12, this disk may be made the same size, and like said locking disks and the gear 52 so meshed that the passing hollow in these disks shall be in a position to permit the rotation of the gear 70 teeth 61. One arrangement will serve just as well as the other. The parts are so arranged that positive totals are read on the number disks 23 through the window 30 and negative totals are read on the disk 24 75 through the window 31. The numbers on the disks 23 progress in a counter clockwise direction (as shown by the auxiliary figures around said disks in Fig. 6) and those on the disks 24 progress in a clockwise direction. 80 Assuming the parts to be in the position shown in Fig. 3, the positive number wheels 24 being exposed, and the handle 42 moved downward, it will be readily seen that both shutters 34 and 35 will rotate in a clockwise 85 direction, exposing the negative number disks 24 and concealing the positive number disks 23 and also that in consequence of the motion transmitted by the pinion 52 to the carrying wheel 12 in the units place both 90 number disks in the units place will be turned in a counter clockwise direction also. This, as will be seen by reference to Fig. 6, will add one in the units place of the negative number disks 24. Of course one will be 95 simultaneously subtracted from the number indicated on the positive numeral disks 23 but since as these disks are at that time concealed by the coöperating shutter 34 this will be immaterial.

Attention is called to the fact that at the time of the insertion of the units in the units place, subsequent to a passage of the total in the totalizer through zero, that the segmental gear 37 forms a locked chain with all the 100 carrying gears 12 of the totalizer. Consequently it is immaterial what the reading of the number wheels is when this additional unit is inserted, for if any carrying is to be done it will be transmitted throughout the 105 entire chain. Attention is also drawn to the fact that the pinion 52 which connects the segmental gear 37 to the carrying gear 12 in the units place of the totalizer is mounted on a swinging arm 16. This arm is the one 110 which is in engagement with the dog 208 when the master wheel 49 is in engagement with the carrying gear 12 in the units place of the totalizer. Consequently at that time the pinion 52 is lifted out of mesh, thereby 115 leaving the carrying gear 12 in the units place of the totalizer free to be moved by the master wheel 49.

While I have shown my invention employing two sets of number wheels it is obvious that this is not at all necessary since one set of number wheels could be provided having two oppositely running sets of figures paired 0-9, and a single shutter could be used to shift from one set of figures to 120

125

130

the other. The particular reason why two sets of number wheels were used in this present construction instead of one was from considerations of space only, since in the 5 Wahl machine the distance of one carrying gear 12 to the next is one-tenth of an inch, thereby conforming to the ordinary typewriter pitch, and there would not be space enough to employ a number wheel with two 0 sets of figures on it without making those figures undesirably small. However, I consider such a construction is an obvious equivalent of my invention.

I wish to direct attention to the advantage 15 of this algebraic totalizer over others in the prior art, especially that disclosed in the patent to Hopkins No. 1038890, September 17, 1912, in which there is disclosed an automatically exhibited legend which instructs 20 the operator when an additional unit should be added to the totalizer, in order that the totalizer will exhibit the correct resultant of a sum of promiscuous positive and negative numbers. In the Hopkins machine, the 25 shutter is automatically changed from one set of numbers to another, by the passage of the totalizer through zero. The instruction device operates in a cycle of two steps, one step being given to it by the passage of 30 the totalizer through zero in either direction, and another step being given to it by the insertion of an extra digit by means of the key 93. In the device disclosed in my present application, it will be seen that by 35 the simple expedient of making the shutter as well as the mechanism for adding a unit into the totalizer controlled by a single handle, I am enabled to dispense with the elaborate mechanism shown in the cited 40 patent.

It is to be noted that whenever the total passes through zero the number on the exposed wheels will exhibit a 9 in its highest place, and this can be taken as an indication that the total should be read from the other set of wheels. The handle 42 is then moved to its alternative position, and, in accordance with what has been described, the correct total may then be read. If it is desired to have some special designation, to show when the shutter should be changed, an additional wheel may be used next to the highest wheel of the totalizer and connected to such highest wheel by suitable carrying mechanism, and said wheel may have a designation such as a red mark or any suitable legend on its periphery. However, I do not consider such an additional sign particularly desirable, since the highest 55 wheel of the totalizer will always give the correct information by exhibiting either a 9 or a 0. A 9 will be the indication to shift the shutter, and a 0 an indication to read from the number as it is exhibited. It is assumed, of course, that a totalizer of sufficient

capacity to handle the problem on which the machine is engaged is employed; but since totalizers are usually made to have one or two decimal places above the highest number which is encountered in the work done on 70 the machine, the highest wheel will usually afford sufficient indication for shifting the shutter.

As before noted, the Wahl machine is provided with a lever by which the rotation of 75 the master wheel consequent on the depressing of any key may be reversed, thereby enabling the insertion of numbers either additively or subtractively. In dealing with positive totals, the total is usually cleared 80 from the machine by throwing the handle to the subtraction position and printing out the exhibited total. The fact of the totalizers returning to zero at the end of this operation is a check on its correctness. To 85 print out a negative total, it is necessary, of course, to set the handle to its adding position and print the number exhibited through the window 31.

Fig. 7 shows the appearance of the totalizer when it exhibits a positive total. It will be noted that the shutter 35 concealing the negative number disks 24 has inscribed on it "+ Total. Erase by subtraction." Thus instructing the operator how to manipulate 95 the machine to clear the exhibited total.

The shutter 34 concealing the positive number disks 23 has likewise (Fig. 8) the legend "— Total. Erase by addition." Thus giving instructions for erasing the 100 total in case the same should be negative. For the sake of clearness, the legends referred to above have been omitted from the drawings of the shutters, as shown in Fig. 2.

Of course, the legends "+ Total" and "— 105 Total" may be replaced by "Debit and credit", "Credit and overdraft", or any terms appropriate to the work on which the totalizer is used.

It is to be noted that, in my improved 110 totalizer herein described, the act of exhibiting the proper total of the items entered in the machine also automatically instructs the operator how to set the machine in order to erase said total, thus greatly lessening 115 the liability to error.

It will be noted that the operation of this totalizer is extremely simple, there being but one rule necessary for its operation; viz.: if a 0 is shown in the highest place of 120 the exhibited number, read the number; if a 9, shift the handle 42 and read.

Many changes can be made in the precise form, arrangement and structure herein described without departing from the spirit 125 of my invention, since I claim:

1. In a calculating machine the combination of: a totalizer adapted to exhibit either of two numbers, a designating device shiftable to designate either number, and manual 130

means to shift said designating device and simultaneously add a predetermined amount to the number designated.

2. In a calculating machine the combination of: a totalizer adapted to exhibit either of two numbers, a master mechanism adapted to insert numbers in said totalizers digit by digit in either direction, a designating device shiftable to designate either number, and manual means operating independently of said master mechanism to shift said designating device and simultaneously add a predetermined amount to the number designated.

15 3. In a calculating machine the combination of: a totalizer embodying digit bearing members, means for actuating said members to register an amount thereon, means to add a digit thereto after an amount has been registered, shiftable means to designate certain digits on said digit bearing members, and manual means operative on said digit adding means and said digit designating means whereby a digit may be added to said digit bearing members and the digit designating means simultaneously shifted at will.

4. In a totalizer the combination of: a set of digit bearing members, said members being adapted to exhibit either of two numbers, a set of carrying gears operatively connected to said digit bearing members, a set of carryable gears connecting said carrying gears, the said carrying gears and carryable gears forming a single locked chain, a master wheel adapted to insert numbers in said totalizer digit by digit, means to unlock said gear chain at the actuated carrying wheel, a handle which may occupy either of two alternative positions, and mechanism connecting said handle with said locked gear chain, whereby said gear chain may be displaced a predetermined amount upon the motion of the handle.

5. In a totalizer the combination of: a set of digit bearing members, said members being adapted to exhibit either of two numbers, a set of carrying gears operatively connected to said digit bearing members, a set of carryable gears connecting said carrying gears, the said carrying gears and carryable gears forming a single locked chain, a master wheel adapted to insert numbers in said totalizer digit by digit, means to unlock said gear chain at the actuated carrying wheel, a handle which may occupy either of two alternative positions, and mechanism connecting said handle with said locked gear chain, whereby said gear chain may be displaced a predetermined amount in either direction upon the motion of the handle.

6. In a totalizer the combination of: a gear, a second gear, a pinion connecting the two, thereby forming a gear chain, a dog adapted to hold said chain in a certain position, a pair of number disks also

connected to said chain, and a cam adapted on being moved to disengage said dog, rotate said gear chain and engage number disks and then reengage said dog with said chain, thereby holding said chain and engaged pair of disks in a second position.

7. In a totalizer the combination of: a gear, a second gear, a pinion connecting the two, thereby forming a gear chain, a dog adapted to hold said chain in a certain position, a pair of number disks also connected to said chain, a designating mechanism adapted to designate either of said disks also connected to said chain, and a cam adapted on being moved to disengage said dog, rotate said gear chain, and engage number disks and designating mechanism and then reengage said dog with said chain, thereby holding said chain, disks, and designating mechanism in a second position.

8. In a totalizer the combination of: a gear, a second gear, a pinion connecting the two, thereby forming a gear chain, a dog adapted to hold said chain in a certain position, a pair of number disks also connected to said chain, a shutter mechanism adapted to expose either of said disks also connected to said chain, and a cam adapted on being moved to disengage said dog, rotate said gear chain, and engage number disks and shutter mechanism and then reengage said dog with said chain, thereby holding said chain, disks and shutter mechanism in a second position.

9. In a calculating machine, the combination of: a set of digit bearing members, said members being adapted to exhibit either of two numbers, a set of carrying gears operatively connected to said digit bearing members, a set of carryable gears connecting said carrying gears, the said carrying gears and carryable gears forming a single locked chain, a master wheel adapted to insert numbers in said locked chain digit by digit, means to unlock said gear chain at the actuated carrying wheel, a designating device whereby either of said numbers may be designated, a handle which may occupy either of two alternative positions, and mechanism connecting said handle with said locked gear chain and said designating device, whereby said gear chain may be displaced a predetermined amount and said designating device may be moved to an alternative position upon the motion of the handle.

10. In an algebraic totalizer, the combination of a set of gears, carrying mechanism connecting said gears, two sets of numbers associated with said gears, a shutter device, a gear advancing device, and manually operated means to operate said shutter and gear advancing devices.

11. In an algebraic totalizer, the combination of a set of gears, carrying mechanism

connecting said gears, two sets of numbers associated with said gears, a shutter device, a gear advancing device, and manually operated means to operate said shutter and gear advancing devices simultaneously.

12. In a algebraic totalizer, the combination of a set of gears, carrying mechanism connecting said gears, two sets of numbers associated with said gears, a shutter device, a gear advancing device, and a handle adapted to operate said gear advancing and shutter devices simultaneously.

13. In a totalizer, a casing having two sight openings, a number adapted to be read through one of said openings, a second number adapted to be read through the second of said openings, two alphabetical legends, and means having two alternate positions and adapted when in one position to exhibit a number at one sight opening, and an alphabetical legend covering the other sight opening, and when in its alternate position to exhibit a number at said second opening, and an alphabetical legend covering said first sight opening.

14. In a computing machine, a casing, computing mechanism therein adapted to

compute positive and negative numbers, said casing being formed with two sight openings to exhibit these numbers, and means permitting one of said numbers to be read while hiding the other, and bearing an exposed legend constituting an instruction as to the operation of the machine.

15. In a machine of the character described, the combination with a totalizer adapted to exhibit positive and negative totals, and actuating and clearing mechanism therefor, of a casing having a sight opening through which totals may be displayed, and a shutter for said sight opening bearing a legend extending over and adapted to be seen at approximately the same position as the totals through said sight opening, when the numbers are hidden by the shutter, to constitute an instruction with reference to the machine.

In witness whereof, I have hereunto subscribed my name in the presence of two witnesses.

ARTHUR F. POOLE.
